MATCH BOOK SLIP COVERS

Lois April, New York, N. Y.

Application October 8, 1956, Serial No. 614,705

1 Claim. (Cl. 206—29)

2

Fig. 4 is a detail sectional view, still further enlarged, substantially on line 4—4 of Fig. 3.

Fig. 5 is an enlarged detail sectional view on line 5—5 of Fig. 3.

5 Fig. 6 is an enlarged detail sectional view on line 6—6 of Fig. 3.

Fig. 7 is an enlarged detail sectional view on line 7—7 of Fig. 3.

10 Fig. 8 is a plan view on a reduced scale of the cover during an early step in manufacture of the same.

Fig. 9 is an enlarged perspective view, partly broken away, of a modified construction.

15 Fig. 10 is a view similar to Fig. 8 of the modified form, portions being broken away.

Fig. 11 is a front elevational view of the modified construction, in fully closed position.

20 Fig. 12 is a front elevational view of the modified construction in which the match book has been opened for removal of a match.

Fig. 13 is a front elevational view of the modified construction in which the front panel of the cover and match book have been slid upwardly to a slight extent to expose the striking surface of the match book.

25 Referring to the drawings in detail, in the form of the invention shown in Figs. 1—8, the match book cover 10 constituting the invention in effect constitutes a "slip cover" for a conventional match book or match supply 12.

30 The cover 10 is formed entirely from a fabric material, preferably one of the stiffer or heavier, ornamentally surfaced fabrics such as taffeta, so as to impart maximum durability thereto, thus to permit the same to be used over and over again on different match books.

35 In its basic essentials, the cover is provided with a back panel 14 adapted to wholly overlie the back panel of the match book, and projecting at its sides a short distance laterally outwardly from the respective side edges of the back panel of the book.

40 Back panel 14 merges at the top or bight part of the match book into a front panel 16 which covers the full area of the match book front panel. Panel 16 is secured at its side edges to a rectangular pocket-forming portion or flap 18 which is slightly shorter in length than the front panel, thus to terminate short of the bight or bend portion of the match book. Portion 18 cooperates with the front panel 16 in defining on the back of the front panel a pocket adapted to receive the front panel of the match book as best shown in Figs. 1 and 2.

45 50 At the lower end of the back panel 14, there is provided on the front surface thereof a low, transversely extending pocket-forming portion or flap 20, which receives the lower end of the match book.

The attractiveness of the cover is heightened by the provision of ornamental means on the front panel 16, said means being, in the illustrated example, a center bead 22 about which are arrayed smaller beads 24. These are cemented to the fabric material. Obviously, the ornamentation can take various forms, as for example, a miniature bouquet of artificial flowers, etc.

55 60 The ornamental means has, it may be noted, a utilitarian as well as an ornamental function, in that it forms a projection on the front panel against which one may position his or her thumb for the purpose of opening the match book.

65 It may thus be noted, from the description so far provided, that the match book cover constituting the invention includes an elongated, substantially rectangular, fabric body 25 forming integrally connected front and back panels 14, 16, respectively, and having at its respective ends oppositely opening pockets one for receiving the base

Fig. 1 is a perspective view of a match book cover according to the invention, fitted onto a conventional match book.

Fig. 2 is an enlarged sectional view longitudinally through the match book and cover, substantially on line 2—2 of Fig. 1.

Fig. 3 is an enlarged perspective view of the cover per se, in fully opened, flat condition.

or bottom end of the match book and the other for receiving the front panel of said book.

The match book or match supply itself is conventional, and includes a folder having a back panel 26 engaging against the inner surface of the back panel 14 of the cover, and a front panel 28 integral with the back panel 26 and fitting into the pocket provided at the back of the front panel 16 of the removable cover. The match book further includes the lip 30 coated with a suitable abrasive and the card of matches or match assembly 32 stapled to the lip 30 and to the back panel 26 by means of the usual staple 34.

In use, one simply opens the removable cover and slips the front panel 28 of the match book into the large pocket of the device. One then engages the lower end of the match book in the small pocket. The match book is in this way fully covered, and one may then engage the front panel 16 of the device in back of the lip 30 of the match book (see Fig. 2) in the same way that the front panel of the match book is engaged in back of said lip when the match book is not in use.

The matches are removed in the usual way, and when the supply of matches is completely exhausted, so that the match book is to be discarded, one easily slips the empty match book out of the cover 10, and places in the cover 10 a fresh book.

It is to be understood that the match book cover may be rectangular, oval, heart-shaped or any other configuration and that the beads 22 and 24 may be cemented, stitched or secured to the front panel 16 in any desired manner. This ornamentation may be in the form of beads, appliques or any other type of decoration.

Referring to Fig. 8, in constructing the cover 10, one uses a rectangular piece of fabric, as shown in Fig. 8, and folds inwardly the side and end edge portions, stitching the same to provide side and end hems 36, 38, respectively. Then, the fabric is folded along a transverse line 40 adjacent one end to define the smaller pocket. The ends of the flap or pocket-forming portion 20 are cemented into the hemmed sides of the back panel 14. A substantial distance inwardly from the other end of the fabric, the material is folded inwardly along a transverse fold line 42 to provide the large pocket. Again the sides of the pocket-forming flap or portion 18 are cemented to the sides of the front panel 16. This completes the device except for adding the ornamentation on the front panel, if such is desired.

In Figs. 9-13 a modification is shown. This is identical to the first form except for extension of a rectangular spring wire frame 44 within the side hems.

Thus, in the modified form the cover 10 is identical to the first form. Before folding over the side and end hems, however, a rectangular wire frame 44 is positioned as shown in Fig. 10. This, as will be noted from Fig. 10, is shorter in length than the fabric blank, and includes side members 46 extending within the side hems 38, and end members 48 extending one along the fold line 40 and the other extending along the fold line 42. The side and end hems are then stitched to the body 25. Then, the pocket-forming flaps are folded over and cemented in place. Thereafter, the spring wire frame is pretensioned or bent at locations 50 intermediate the ends of the side members 46. This is for the purpose of normally maintaining the cover in the form shown in Fig. 2, so that the tension of the spring wire will normally urge the front panel 16 to its Fig. 11 position. It is to be noted that in this position, the front panel has its lower edge disposed in abutting relation to the pocket flap 20 so as to normally cover the striking surface of the match book, thus concealing all portions of the match book.

To remove a match, one lifts the front panel to the

Fig. 12 position against the restraint of the now U-shaped side members 46 of the frame. The match is removed, and on release of the lifted front panel, the tension of the side members 46 is permitted to assert itself as a result of which the front panel snaps back to its Fig. 11 position. There is no necessity of engaging the front panel under the lip of the match book. Then, in striking the match, one merely shifts the front panel 16 in a direction away from the pocket flap 20 in the manner shown in Fig. 13, to expose the striking surface of the lip 30. When the match has been struck, one merely releases the pressure previously exerted on front panel 16 with the thumb, and the tension of the side members 46 of the frame again asserts itself to return the front panel to the normal position thereof shown in Fig. 11.

Obviously, the device is readily interchangeable so as to be usable for a long period of time. Further, it can be washed if desired. In this connection, the wire frame would be of a non-corrosive material so as not to stain the fabric.

Still further, the cover is so designed that one may have a set of the covers, in fabrics of different colors, so that a lady may match her ensemble or select a cover 10 particularly ornamented to complement and harmonize with various day or evening wear accessories, such as earrings, pendants, brooches, etc.

While I have illustrated and described the preferred embodiments of my invention, it is to be understood that I do not limit myself to the precise constructions herein disclosed and that various changes and modifications may be made within the scope of the invention as defined in the appended claim.

Having thus described my invention, what I claim as new, and desire to secure by United States Letters Patent is:

In combination, a match supply of the class herein set forth including a match assembly, a folder therefor having front and rear panels and a lip, a cover for said match supply comprising a flexible body with a short pocket at one end thereof extending the full width of the body and receiving the front panel of the folder and the lip in exposed condition, an elongated pocket on the other end of the body extending the full width of the body and receiving the rear panel of the folder, said pockets being disposed in confronting relation and opening in opposite directions away from the ends of the body on which they are disposed, the flexible body being of rectangular configuration and including front and back panels integrally connected intermediate the ends of the body and respectively proportioned to overlie the front and back panels of the folder, said short pocket being formed on the inner surface of the back panel of the cover, said elongated pocket being formed on the inner surface of the front panel of the cover, said pockets being defined by inwardly folded end portions of the back and front panels of the cover, said body being formed with side hems, and a rectangular spring wire frame enclosed in the side hems, said frame being tensioned normally to form the cover into a substantial U-shape to bias the folder front panel to a normally closed position inside the lip.
